Atty.

UNITED STATES PATENT OFFICE.

WALTER S. GOLL, OF FORT WAYNE, INDIANA.

MEANS FOR REGULATING THE COOLING OF INTERNAL-COMBUSTION ENGINES.

Application filed December 31, 1920. Serial No. 434,291.

To all whom it may concern:

Be it known that I, WALTER S. GOLL, a citizen of the United States, residing at Fort Wayne, county of Allen, State of Indiana, have invented certain new and useful Improvements in Means for Regulating the Cooling of Internal-Combustion Engines, of which the following is a specification.

In connection with internal combustion engines, it is necessary to provide a cooling means for them in order to keep the temperature within permissible limits, and it is desirable that such cooling means be regulated to keep at all times the engine at a temperature for efficient operation.

The primary object of my invention is to provide an improved means for regulating the cooling of an internal combustion engine, which means is simple in structure, easily applied to an engine, and which although small in size has ample power for performing the work required of it.

One application of my invention is in connection with automobiles wherein the flow of air for cooling the engine either directly, as in the case of air-cooled engines or indirectly, as in the case of water-cooled engines, is controlled by shutters placed in the path of the air stream, and more particularly an object of my invention is to provide an improved structure and arrangement, or means, for automatically actuating such shutters.

A practicable control device of the type to which my invention relates must have the following characteristics:

(1) Accuracy of temperature regulation preferably not to exceed a variation of 10 degrees F.

(2) Sufficient power to operate shutters under all driving conditions from idling to maximum speed and from closed to wide-open throttle.

(3) Maximum power available at maximum rate of heat input to the cooling medium.

(4) Return of shutters to closed condition immediately upon stoppage of the engine to conserve heat.

(5) Calibration means to enable maintenance of most efficient temperature for summer conditions and to prevent loss of anti-freeze mixture (such as alcohol) for winter conditions.

(6) Closing of shutters to conserve heat when the car "over-runs" the engine, e. g.,

when the engine is used as a brake in coasting down grade.

(7) Simplicity of mechanism to insure reliability of operation.

A further object of my invention is to provide an improved device which will meet the above conditions in a satisfactory manner.

For a consideration of what I believe to be novel and my invention, attention is directed to the accompanying description and the claims appended thereto.

In the drawing, Fig. 1 is a side elevation partly in section of an embodiment of my invention, and Figs. 2 and 3 are views of details.

Referring to the drawing, 5 indicates an internal combustion engine, 6 a radiator, and 7 a hose connecting the upper portion of the cooling jackets of the engine cylinders to the radiator. Only portions of the engine and radiator are shown in the drawing and they are to be taken as typical of any suitable or known engine and radiator arrangement such as are in common use on automobiles for example. Arranged in front of radiator 6 is a suitable frame 8 in which are pivotally mounted shutters 9. Shutters 9 are fastened to each other by links 10, the arrangement being such that the shutters open and close in unison. In Fig. 1 shutters 9 are shown closed and their open positions are indicated in dotted lines. The shutters are biased toward closed position by their weight assisted, if found desirable, by a spring or other suitable means, the arrangement being such that when released they will move to closed position automatically. As is well understood a shutter arrangement as shown operates to regulate the flow of air through the radiator for cooling the water circulating therein, the amount of air flowing through depending on the degree to which the shutters are opened.

Now, according to my invention, I actuate the shutters by gas pressure taken directly from one or more cylinders of the engine, the application of such pressure to the mechanism which directly moves the shutters being controlled by a means, such as a thermostat, responsive to the temperature of the engine or of the cooling medium for the engine. By this arrangement I obtain actuating gas under pressure from a source already available and at a pressure sufficiently high to make the actuation of the

shutters positive and to not require a large mechanism for moving the shutters.

- In the arrangement shown in the drawing, shutters 9 are connected by a link 11 to one arm of a lever 12, the other arm being connected to a rod 13 carried by a piston 14 moving in a cylinder 15. Lever 12 is provided between its ends with a pivot pin 16 and is suitably pivoted on a wall of frame 8. Cylinder 15 is suitably supported by frame 8. Connected to cylinder 15 is a pipe 17 which leads to a closed casing 18 and leading from casing 18 is a pipe 19 which connects through a small opening 20 directly with the combustion chamber of an engine cylinder. It will thus be seen that pipes 17 and 19 connect cylinder 15 directly to the combustion chamber of one of the engine cylinders.
- The connection of pipe 19 to the engine cylinder is made through a fitting 21 which contains opening 20 and also forms a casing for an outwardly opening check valve 22 adapted to close opening 20 to prevent flow of pressure from pipes 17 and 19 to the engine. Check valve 22 is provided with guide wings 23 beyond which is a stop 24 in the form of a pin against which the ends of the wings strike to limit outward movement of the valve.

Connected to pipe 17 is a branch pipe 25 which terminates adjacent radiator 6 and has its end supported in a bracket 26 carried at one end of a bar 27. Bar 27 is made of a material which is a good conductor of heat and is fastened directly to the radiator where it will be subjected to the temperature of the cooling medium in the radiator. The end of pipe 25 adjacent the radiator is open and is provided with a seat for a valve 28. Valve 28 has guide wings 29 located in the end of pipe 25 and sliding therein, and is adapted to move toward and away from the end of pipe 25 to vary the size of the opening. On the end of bar 27 remote from bracket 26 is fixed a block 30 to which one end of a strip of thermostatic metal 31 is fastened. The other end of strip 31 projects through an opening 32 in a wall of bracket 26 and rests against the outer end of valve 28. Valve 28 is held against the end of strip 31 by a spring 33. Block 30 is formed of a material which is a good conductor of heat so as to readily transfer heat from bar 27 to thermostatic strip 31. Pipe 25, valve 28 and strip 31 form a thermostatically regulated by-pass or discharge opening in the conduit comprising pipes 17 and 19.

The operation is as follows:—Assume the engine is not running and that it and the cooling medium are cold. Under these conditions shutters 9 are closed and thermostatic strip 31 stands in a position to permit spring 33 to hold valve 28 open as

shown in Fig. 1 of the drawing. With the shutters closed piston 14 stands adjacent the closed end of cylinder 15. There will be no pressure back of it or in pipes 17 and 19. If now the engine is started, on each explosion in the cylinder to which pipe 19 is connected a certain amount of gas under pressure will escape through opening 20 into pipe 19 and pass therethrough into casing 18 and thence to pipe 17. Since valve 28 is open the gas pressure will escape from pipe 17 through branch pipe 25 to atmosphere and hence no pressure will be built up back of piston 14. The shutters 9 will remain closed and there will be no circulation of cooling air through the radiator. As a result the engine will quickly heat up the cooling medium and itself become heated. Heat from the cooling medium will be quickly transferred through bar 27 and block 30 to thermostatic strip 31 and such strip on being heated will bend in a direction to move valve 28 toward closed position. As valve 28 moves toward closed position the escape of pressure past it is retarded and a pressure is thereupon built up in pipe 17 and chamber 18 which pressure is applied to piston 14 tending to move it in a direction to open shutter 9. When a predetermined high temperature is reached valve 28 will be closed to such an extent that the pressure built up will be sufficient to move piston 14 to open shutters 9 more or less so cooling air can flow through the radiator. As the temperature of the cooling medium, i. e., the engine rises and falls the temperature of the thermostat, will likewise rise and fall and will effect the operation of valve 28 to increase or decrease the pressure behind piston 14 thereby moving shutters 9 to regulate the flow of cooling air through the radiator. The engine will be thus maintained automatically at the desired temperature. In opening the shutters, piston 14 must move them against the biasing force which tends to hold them closed. When the pressure behind piston 14 decreases the biasing force moves the shutters toward closed position. In the case of valve 28, thermostat 31 moves it toward closed position against the action of spring 33 and when the end of thermostat 31 moves away from valve 28 spring 33 causes the valve to follow the thermostat and open. Check valve 22 prevents flow of pressure from pipe 19 into the engine cylinder. The various parts are adjusted so the desired temperature for the engine will be maintained under all normal conditions of operation, and the arrangement may be such that all graduations of shutter openings are obtained.

The pressure supplied by the engine piston is in the form of successive impulses and the purpose of casing 18 is to serve

as a means for damping out such impulse and providing a substantially continuous and even pressure on piston 14. Any suitable means may be employed for this purpose although I now prefer to use a form of capacity in the pipe line such as the casting 18 as shown. Such a capacity performs the intended function in an efficient manner and at the same time is simple in structure and not likely to become deranged.

The drawing is of a diagrammatic nature, some of the parts being shown exaggerated in size for purposes of illustration. In actual practice opening 20 is very small. It does not appreciably affect the compression in the engine cylinder. For example, opening 20 may have a diameter of the order of 0.030 of an inch.

Since the pressure for actuating the shutters is taken directly from one of the engine cylinders, I am enabled to obtain a pressure of comparatively high value. This means that the piston and cylinder or other form of movable abutment used for directly actuating the shutters may be made comparatively small so they occupy but a small space. At the same time ample power is always available for moving the shutters. This is a feature of importance particularly in the case of automobiles where the space available is limited. In this connection it will be understood that the cylinder and piston arrangement shown is only one form of movable abutment which may be used in carrying out my invention. Any form of movable abutment or pressure device found suitable may be utilized. Also the thermostat may be located at any point found desirable for heating it in accordance with the temperature of the engine.

Furthermore, by taking pressure from an engine cylinder for operating the shutters, I utilize a source of pressure already available. This avoids the use of any additional mechanism for creating an actuating pressure. All that is required is the tapping of the cylinder. It will also be noted that the mechanism required for carrying out my invention is of a simple nature, can be manufactured at a low cost, and is readily applied to any engine or automobile.

In connection with the operation of check valve 22, this valve is of such weight and aperture 20 is of such size that the pressure required to open it is greater than the compression pressure of the engine cylinder. As a result valve 22 opens to permit the escape of gas under pressure only during the explosion stroke of the engine cylinder. By this arrangement no unburned mixture is lost, and furthermore idling of the engine is not interfered with.

Referring to Figs. 1 and 3, it will be noted that the end of pipe 25 is adjustably connected to bracket 26 through the inter-

mediary of a bushing 26*. By turning bushing 26 the end of pipe 25, which end forms the seat for valve 28, can be moved toward and away from the valve so as to vary the temperature at which the shutter will be actuated. The amount of adjustment required is not large and ordinarily there will be sufficient give in the pipes to permit of the necessary adjustments taking place. If such is not the case, however, any suitable means may be provided for permitting such adjustment. It is desirable that such adjustment be provided for in order to enable maintenance of the most efficient temperatures for summer and winter conditions.

While I have shown my improved mechanism as connected to only one cylinder of the engine, it will be understood of course that it may be connected to two or more of them if found desirable. By connecting to two or more cylinders greater power may be obtained, but in actual practice I have found connection to one cylinder to be quite satisfactory.

In accordance with the provisions of the patent statutes, I have described the principle of operation of my invention, together with the apparatus which I now consider to represent the best embodiment thereof, but I desire to have it understood that the apparatus shown is only illustrative and that the invention may be carried out by other means.

What I claim as new and desire to secure by Letters Patent of the United States, is:—

1. An internal combustion engine having shutters for regulating the flow of cooling air and pressure actuated means for moving the shutters characterized by the fact that pressure for said means is taken directly from the combustion chamber of a cylinder of the engine.

2. The combination with an internal combustion engine and heat radiating means over which air passes to cool the engine, of shutters for regulating the flow of air over said heat radiating means, and means actuated by explosion pressure taken directly from the combustion chamber of a cylinder of the engine for operating said shutters.

3. The combination with an internal combustion engine and heat radiating means over which air passes to cool the engine, of shutters for regulating the flow of air over said heat radiating means, a movable abutment for moving said shutters, and a conduit connecting said abutment directly to a cylinder of the engine whereby the shutters are actuated by explosion pressure taken from such cylinder.

4. The combination with an internal combustion engine and heat radiating means over which air passes to cool the engine, of shutters for regulating the flow of air over said heat radiating means, a movable abutment for moving said shutters, a conduit connect-

- 4
- ing said abutment to a cylinder of the engine whereby the shutters are actuated by pressure taken from such cylinder, and means for damping out the pressure pulsations from the engine cylinder so a substantially even pressure is applied to said abutment.
5. The combination with an internal combustion engine and heat radiating means over which air passes to cool the engine, of shutters for regulating the flow of air over said heat radiating means, a movable abutment for moving said shutters, a conduit connecting said abutment directly to a cylinder of the engine whereby the shutters are actuated by explosion pressure taken from such cylinder, and temperature responsive means for controlling the application of such pressure to said abutment.
10. The combination with an internal combustion engine and heat radiating means over which air passes to cool the engine, of shutters for regulating the flow of air over said heat radiating means, a movable abutment for moving said shutters, a conduit connecting said abutment to a cylinder of the engine whereby the shutters are actuated by pressure taken from such cylinder, a valve for permitting escape of pressure from said conduit, and a thermostat responsive to the engine temperature for regulating said valve.
15. The combination with an internal combustion engine and heat radiating means over which air passes to cool the engine, of shutters for regulating the flow of air over said heat radiating means, a movable abutment for moving said shutters, a conduit connecting said abutment to a cylinder of the engine whereby the shutters are actuated by pressure taken from such cylinder, means for damping out the pressure pulsations from the engine cylinder so a substantially even pressure is applied to said abutment, and means responsive to the temperature of the engine for controlling the application of such pressure to said abutment.
20. In combination, an internal combustion engine, cooling means therefor, pressure actuated mechanism for regulating the cooling means, a conduit connecting the pressure actuated mechanism to the combustion chamber of a cylinder of the engine, said conduit having capacity whereby pressure impulses are absorbed, and a discharge opening in said conduit the area of which is regulated in accordance with the temperature of the engine.
25. In combination, an internal combustion engine, cooling means therefor, pressure actuated mechanism for regulating the cooling means, a conduit connecting the pressure actuated mechanism to the combustion chamber of a cylinder of the engine, said conduit having capacity whereby pressure impulses are absorbed, a discharge opening in said conduit the area of which is regulated in accordance with the temperature of the engine, and a check valve in said conduit for preventing flow through it to the cylinder of the engine to which the conduit is connected.
30. The combination with an internal combustion engine of pressure actuated means for regulating the cooling of it, a conduit connecting said pressure actuated means to the combustion chamber of a cylinder of the engine, a valve seat in said conduit, and a valve which normally rests on said seat, said valve being arranged to be opened by the explosion pressure but not by the compression pressure.
35. The combination with an internal combustion engine, of a mechanism to be operated, a conduit connecting the mechanism to the combustion chamber of a cylinder of the engine, and a valve in said conduit which is biased to its seat and is opened by the explosion pressure but not by the compression pressure.
40. The combination with an internal combustion engine, of means for regulating the cooling of it, a pressure actuated device for operating said means, a conduit connecting said pressure actuated device to the combustion chamber of a cylinder of the engine, the connection to the cylinder being through an orifice of restricted area, an outwardly opening check valve, in said conduit which opens at pressures greater than the compression pressure, and a valve for permitting escape of pressure from said conduit.
45. In combination with an internal combustion engine cylinder provided with a water jacket, a pressure chamber connected with the interior of the cylinder, a movable member associated with the pressure chamber and actuated by the pressure thereof, a radiator through which the cylinder jacket water circulates, a shutter positioned adjacent the radiator for controlling the passage of cooling air therethrough and operating connection between the shutter and the movable member of the pressure chamber.
50. In witness whereof, I have hereunto set my hand this 28th day of December, 1920.

WALTER S. GOLL.
